DESIGN FOR A FOOD TRAY

Albro Georgi Wynkoop, Piedmont, Calif.

Application December 31, 1940, Serial No. 97,744

Term of patent 14 years

To all whom it may concern:

Be it known that I, Albro Georgi Wynkoop, a citizen of the United States, residing at Piedmont, county of Alameda and State of California, have invented a new, original, and ornamental Design for a Food Tray, of which the following is a specification, reference being had to the accompanying drawing, forming part thereof.

Fig. 1 is a view of a food tray in elevation, showing my new design.

Fig. 2 is a plan view of a food tray showing my new design.

Fig. 3 is a central vertical sectional view through the food tray for the purpose of showing the contour.

I claim:

The ornamental design for a food tray, as shown.

ALBRO GEORGI WYNKOOP.
